UNITED STATES PATENT OFFICE.

GUNNAR MADVIG, OF OAKLAND, CALIFORNIA.

DESIGN FOR AN END FOR DRAPERY POLES OR RODS.

Application filed April 18, 1928. Serial No. 26,372. Term of patent 3½ years.

To all whom it may concern:

Be it known that I, GUNNAR MADVIG, subject of the King of Denmark, and a resident of the city of Oakland, county of Alameda, State of California, have invented a new, original, and ornamental Design for an End for Drapery Poles or Rods, of which the following is a specification, reference being had to the accompanying drawings, forming part thereof.

Figure 1 is a side view of the end illustrating my new design.

Figure 2 is a plan view of the end.

I claim:

The ornamental design for an end for drapery poles or rods substantially as shown.

GUNNAR MADVIG.
